DESIGN FOR A PERFUME BOTTLE

Henry Gilbert, North Hollywood, Calif., assignor to Mission Hosiery Mills, Los Angeles, Calif., a corporation of California

Application May 22, 1945, Serial No. 119,673

Term of patent 7 years

(Cl. D58—9)

To all whom it may concern:

Be it known that I, Henry Gilbert, a citizen of the United States, residing at North Hollywood, in the county of Los Angeles and State of California, have invented a new, original, and ornamental Design for a Perfume Bottle, of which the following is a specification, reference being had to the accompanying drawing, forming part thereof, in which:

Fig. 1 is a perspective view of a perfume bottle, showing my new design;

Fig. 2 is a side elevational view thereof; and
Fig. 3 is a top plan view thereof.

I claim:

The ornamental design for a perfume bottle, as shown.

HENRY GILBERT.
